UNITED STATES PATENT OFFICE.

WILLIAM G. MAYER, OF PITTSBURGH, PENNSYLVANIA.

AUTOMOBILE-BODY SUPPORT.

1,230,748.

Specification of Letters Patent. Patented June 19, 1917.

Application filed October 3, 1916. Serial No. 123,507.

To all whom it may concern:

Be it known that I, WILLIAM G. MAYER, a citizen of the United States, and resident of Pittsburgh, in the county of Allegheny and State of Pennsylvania, have invented 5 a new and useful Improvement in Automobile-Body Supports; and I do hereby declare the following to be a full, clear, and exact description thereof.

10 My invention pertains to automobile-body supports, that is to say to the means for connecting the body of an automobile, especially a commercial truck, to the chassis or frame of the machine. In the ordinary construction 15 of automobiles, particularly commercial trucks, a great deal of work and time has had to be spent whenever it was necessary to remove the body from the chassis; moreover, the connecting devices used were such 20 that it was not possible to effect the removal of the body without damage to the latter, as by means of tearing up floor boards or the like. Besides this, the ordinary connecting devices between the body and the 25 truck are such that very little room is left beneath the body, to permit access to the machinery carried at that part of the chassis. It is an object of my invention to provide 30 for so connecting the body to the chassis that it may be easily and quickly removed and replaced on occasion arising. It is another object of my invention to provide for connecting the body to the chassis in such a way that no damage to the body, and no 35 cutting or the like of the body, is necessary, when the body is to be removed or replaced. It is another object of my invention to provide a means for connecting the body to the chassis which will leave an increased space 40 between the bottom of the body and the mechanisms carried by the chassis, and thus facilitate access to the latter. It is another object of my invention to provide a simple and economical supporting device for connecting 45 the body to the chassis, which device will be of such a nature as to admit of its use with varying characters and sizes of bodies and varying characters and sizes of chassis. And other and further objects of 50 my invention will appear from the following specification taken in connection with the claims annexed thereto.

In the drawing:

Figure 1 is a side elevation showing a portion 55 of a delivery truck having the body connected to the chassis by means of sup-

ports constructed in accordance with my invention:

Fig. 2 is an enlarged front view of one of the side supports, showing the same in 60 position upon the side bar of a chassis:

Fig. 3 is a view looking from the direction of the line 3—3 of Fig. 2; and

Fig. 4 is a side view showing one of the 65 end supports.

Like reference characters refer to like parts throughout the following specification and the several figures of the accompanying drawing.

Referring now to the drawing, 10 indicates the chassis of a delivery truck, which chassis includes a pair of side bars 11, and an end bar 12. These bars are usually in the form of channel irons. The truck body 13 is provided, on its under side, with a 70 plurality of transversely extending wooden bolsters 14, of which one, 14', is so located as to be situated above the end bar 12 of the chassis when the body is in place. In carrying my invention into effect, I connect 75 the body to the chassis by means of sockets into which the bolsters 14 and 14' fit, and to which bolts are removably secured, the sockets being connected to the bars of the chassis. The sockets employed are, in the 80 embodiment now being described, of two kinds, one kind being employed for receiving the bolsters 14, and the other kind being employed for receiving the end bolster 14'. 85

Referring now particularly to Figs. 2 and 90 3, which show a support for receiving the bolsters 14, each of these supports comprises a flat stem 15, which is of such a length as to be somewhat longer than the depth of the largest channel iron ordinarily 95 forming part of a truck chassis. At its upper part, the stem 15 is projected outward, at one side, to form a foot 16, the lower face of which is adapted to rest upon the upper face of the channel iron forming the chassis side bar. Above the foot 16, the stem 15 is formed with a U-shaped socket 17, which socket includes a pair of side flanges 18 and 19, respectively. The socket 17 is made of a width to accommodate one of the bolsters 14, the latter being removably secured in place by means of a carriage bolt 20. 100

In order to secure the supports in place, each of them has associated with it a clamping plate 21. This clamping plate engages 110 the side bar 11 on the side opposite to that which is engaged by the stem 15, and is se-

cured, at its upper end, to the stem 15, by means of a carriage bolt 22 passing through the clamping plate and the stem. The clamping plate is secured, at its lower end, 5 to the stem 15, by means of a second carriage bolt 23, passing through both parts. Ordinarily, the holes for the bolt 23 are not bored in advance, but are bored at the time of fitting the supports in place. In this way, it is 10 possible to have the bolts 22 and 23 fit closely against the upper and lower faces of a side bar of any depth.

Each of the supports which are to be attached to the end chassis bar 12, and which 15 are to receive the bolster 14', includes a stem 15', a foot 16', a clamping plate 21', and bolts 22' and 23', which are similar to the parts 15, 16, 21, 22 and 23 of the support described above, and which are attached to 20 the end bar 12, in the same way as that in which the latter are attached to the side bar 11. The socket 17' with its side flanges 18' and 19', is, however, turned at right angles to the position which is occupied by the 25 socket 17. It is thus in a position such that it can accommodate the end bolster 14', when the support is attached to the end chassis bar 12.

With the aid of the device described 30 above, the operation of removing the body from the chassis is very easily and quickly performed. It is only necessary to take out the bolts 20 and 20', whereupon the body can be lifted vertically away from the chassis. 35 The replacing of the body portion and the chassis is equally easy to effect. It will be noted, further, that either operation can be performed without cutting or otherwise marring the body, and that there is no tendency to damage the body in any way. Apart 40 from the advantage which lies in the ease of removing and replacing the body, the operation of originally connecting the body to the chassis is itself very easily performed. The 45 supports employed are of an exceedingly simple and cheap construction; and their use results in an economy of material. It may be noted, still further, that the supports provide a considerable space between the 50 floor of the body and the top of the chassis, and thus facilitate inspection, repair, or the like, of the mechanisms carried by the chassis beneath the body.

Another important advantage of the device lies in the fact that the ease with which 55 the body-bolsters may be removed from the sockets makes it practicable for a plurality of bodies to be used in connection with the chassis of one machine; so that, for instance, 60 the machine may be used in the delivery of

the contents of one body, while another body is being loaded at the warehouse, the loaded body being substituted for the empty one as soon as the machine comes back.

Having thus fully described my invention 65 what I claim as new and desire to secure by Letters Patent is:

1. An automobile-body support comprising a stem having a portion adapted to lie in engagement with a bar of the chassis and 70 having another portion adapted to rest upon such bar, a clamping bar opposed to the first-named portion of said stem, and a pair of clamping devices for drawing said bar toward said stem, whereby such chassis bar is 75 clamped between said stem and said clamping bar, said clamping devices being separated so as to inclose said chassis bar between them.

2. The combination with an automobile 80 truck comprising a chassis having side bars and an end bar, and a body having a plurality of bolsters extending across the lower part thereof, of means for connecting said body to said chassis, said connecting means 85 including a plurality of supports, each of said supports comprising a stem having a portion adapted to engage against one side of one of the chassis bars, and having a second portion adapted to rest upon such bar, 90 a clamping plate coöperating with the first-named portion of said stem, to secure said support to said chassis bar, a socket for receiving an end of one of said bolsters, and means for securing said bolsters in said 95 socket.

3. The combination with an automobile truck comprising a chassis having frame rails or bars, a body having a plurality of bolsters extending across the lower part 100 thereof, of means for connecting said body to said chassis, said connecting means including a plurality of supports, each of said supports comprising a stem having a portion adapted to engage against one side of one 105 of the chassis bars, and having a second portion extending over such bar, a clamping plate coöperating with the first named portion of said stem, securing members passing through said plate and said stem above and 110 below said bar, a socket for receiving an end of one of said bolsters, and means for securing said bolster to said socket.

In testimony whereof, I the said WILLIAM G. MAYER have hereunto set my hand.

WILLIAM G. MAYER.
